TOOL HAVING IDENTIFICATION INSIGNIA

THERON L. HEDGPETH, OAK PARK, ILL.

Application March 27, 1937, Serial No. 133,476

9 Claims. (Cl. 40—2.2)

The present invention relates to a tool, a method of, and means for providing the same with identification marks. The invention is particularly applicable to tools like drop forged wrenches, but may be applied to other tools as well.

In work shops, factories and the like, where a comparatively large number of workers are employed in a relatively small area, the proper identification of tools has been a serious problem for some time. In some places the employer supplies all the tools, and in others the employees supply their own, but the problem of identification is present in both. Where the employer supplies the tools, the problem arises from the fact that the individual workers are charged with the care of tools placed in their custody; and where the workers own their own tools, the problem arises from the individual ownership thereof. Because of the lack of an easy and simple method and means for permanently marking tools, the loss of tools by alteration of identification marks has remained an ever present source of annoyance.

The primary object of the present invention is to provide a tool marked in such manner that the identification marks cannot be altered or effaced without considerable trouble, and even if completely effaced cannot be marked again without great difficulty and without leaving permanent evidence of the alteration.

A further object of this invention is to provide a tool that can be marked only with a novel type of marking means made in accordance with the present invention, so that even though the original identification marks be effaced, other marks cannot be readily substituted therefor without the novel type of marking means.

A further object of the invention is the provision of a new and novel method of marking tools so that the identifying marks cannot be removed without difficulty, and even though removed the tool will provide evidence of such removal.

A further object of the present invention is to provide a new and novel marking die for a tool provided in the course of its manufacture with an insignia adapted to receive only marking means of the novel type.

A more specific object is to construct the marking means and insignia with complementary inter-fitting portions so that the tool can be marked only with a certain type of marking means.

Another object of the invention is to provide

a new and improved marking device for applying the marking type to the tool.

In brief, the above-mentioned objects are accomplished by forming the tool, which for purpose of illustration is chosen to be an open end wrench with an insignia of a predetermined design. The insignia may take various forms or shapes, but it is essential in the practice of the present invention that it be constructed with a portion adapted to fit into a complementary portion provided on the marking means so that the tool can be marked only by marking means of a corresponding construction. It is preferred that the insignia comprise rib-like portions extending a predetermined distance outwardly from the tool surface so that any alterations may be noted readily from a comparison of the dimensions of the outwardly extending portion with respect to the surface of the tool. It is preferred also that the outwardly extending rib enclose a relatively narrow portion of the surface of the tool, to which enclosed portion the identification mark is applied, in part at least, so that the mark can be removed only with considerable difficulty and by use of special tools.

In the application of the invention to a double open end wrench, the insignia is formed on the handle in the forging process, and the outwardly projecting ribs forming the insignia are extended from the surface of the handle, which is usually thinner than the heads, to the plane of the top faces of the latter.

The preferred insignia is constructed in the shape of an oblong octagon, within which is enclosed a relatively narrow portion of the surface of the wrench handle, and with a central rib that is parallel to the long sides of the oblong octagon. The marking means is constructed to fit within the octagonal insignia, and is provided with a central ridge or depression, into which the central rib of the insignia fits.

After the die has been placed in position over the insignia, pressure is applied thereto to impress the identification mark or marks on the wrench simultaneously on both sides of the central rib.

Once applied, the identification marks may be removed only with considerable difficulty because the ordinary grinding wheel cannot be made to extend to the enclosed surface of the wrench. The use of special tools in making alterations will act as a deterrent upon any one desiring to alter the identification marks.

If the identification marks are effaced, it is necessary to substitute new marks; but, since a

25

30

35

40

45

50

55

special marking means is required, the substitution is rendered difficult, and therefore less likely to be done. If the original identification marks are effaced and new ones substituted therefor, the 5 alteration may be detected by a comparison of the height of the insignia with the surface of the wrench handle within and without the insignia. If an alteration has been made, the inside height of the insignia is greater than the 10 outside height. If the change is concealed, as by grinding away the surface of the wrench handle outside the insignia, any alteration may be detected by comparing the changed height of the insignia with its original height. Even though 15 the insignia be reduced to its original height, the alteration may be detected by comparing the height thereof with the plane of the faces of the wrench heads.

Other objects of the invention will become apparent from the ensuing description of the tool, 20 method of, and means for marking the same. While the description is directed to a double open end wrench, it should be understood that the invention is not limited to wrenches, but is applicable to tools generally.

In the course of the description reference will be had to the accompanying drawings, in which

Fig. 1 is a top plan view of a drop forged double end wrench provided with an insignia constructed and adapted to be marked in accordance with the present invention;

Fig. 2 is a side view of the wrench shown in Fig. 1;

Fig. 3 is a transverse cross-sectional view taken 35 on the line 3—3 of Fig. 1; and showing the height and section of the insignia;

Fig. 4 is a bottom plan view of the assembled die used in marking the insignia illustrated in the previous figures;

Fig. 5 is a transverse cross-sectional view taken 40 on the line 5—5 of Fig. 4, showing the relative positions of the marking dies and die block when properly assembled;

Fig. 6 is a longitudinal vertical cross-sectional view taken on the line 6—6 of Fig. 4, showing the relative positions of the marking dies and die block and the means for securing them in assembled relation;

Fig. 7 is a bottom plan view of an assembled 50 die of modified form;

Fig. 8 is a longitudinal vertical cross-section taken on the line 8—8 of Fig. 7, showing a modified means for securing the marking dies to the die block;

Fig. 9 is a side view, partially in section, of a 55 punch that may be used for marking the wrench. The figure shows the wrench placed on the punch with the die in place thereon, over the insignia, and the punch plunger in position to be struck for marking the wrench.

Fig. 10 is a front view of the device of Fig. 9, showing the manner in which the wrench is utilized to raise the plunger to its upper or retracted position;

Fig. 11 is a horizontal cross-sectional view taken 60 on the line 11—11 of Fig. 9, showing the details of a spring biased finger adapted to maintain the punch plunger in its retracted position; and

Fig. 12 is a partial top plan view of the wrench 65 after it has been marked in accordance with the present invention.

Referring first to Fig. 1, there is illustrated a double end drop forged wrench having a pair of heads 10 that are somewhat thicker than the handle 12 connecting them. The heads 10 are

substantially circular in shape, and the opposite sides 14 and 15 thereof are formed flat and lie in substantially parallel spaced apart planes. The handle 12 is substantially elliptical in cross section in accordance with usual practice.

The insignia 16 of the present invention is formed on the handle 12 in the forging process, and it may be seen to consist of an integral rib extending outwardly from the surface of the handle to the plane of the surfaces 14 of the heads 10, 10 so that the height of the insignia can be readily compared with that of the surfaces. The insignia is formed in the shape of an oblong octagon having a central rib 18 parallel to and intermediate the long sides 20 of the insignia, thereby dividing the 15 area enclosed by the peripheral part of the rib into two portions 22 and 24. The portions 22 and 24 are formed with substantially flat surfaces, as shown in Fig. 3, so that the identification marks may be readily impressed thereon.

The surface of the wrench handle enclosed by the insignia is relatively narrow as compared with the height of the insignia, so that when the handle is marked in the manner hereinafter to be described, the marks cannot be removed except with 25 considerable difficulty and the use of special tools.

The identification marks are applied to the enclosed portions 22 and 24 in such manner that a part of each mark lies on each side of the central rib 18. The mark is applied simultaneously to 30 both portions by a novel marking die provided with a complementary groove or depression into which the central rib extends when the die is positioned over the insignia.

The identification marks used in describing the 35 present invention are letters, but it is apparent that other marks may be used equally well. When letters are used as identification marks, it is necessary to displace somewhat the medial cross lines in letters such as A, B, H, etc., in order to 40 prevent disfiguration of the central rib.

The individual marking dies, as may be seen from Figs. 4 to 6, inclusive, comprise a block 28 of material having a hardness sufficient to leave an impression in the material from which the 45 wrench is made when pressure is applied thereto. The identification marks 30 extend outwardly from the bottom surface of the block and are arranged in reverse so that the identification marks will be impressed properly upon the wrench.

The blocks are provided with a substantially centrally located depression or groove 32 into which the central rib 18 of the insignia extends when the die is placed thereover.

The individual dies are held in assembled relation in a die block 34 provided with a central substantially rectangular opening 36 by means of a set screw 38 extending through the die block into engagement with one of the dies. The set screw should be so adjusted as normally to maintain the 60 dies in the position indicated in Fig. 6, but allow relative movement therebetween in case the dies are not properly positioned and the die block 34 strikes the wrench before the dies themselves do.

The lower side of the die block is provided with 65 a beveled shoulder 40 surrounding the opening 36. This shoulder is so dimensioned that it circumscribes the insignia 16 and thereby positions the dies when the die block is placed in position over the insignia.

The dies 28 have a length somewhat greater than that of the die block 34, but the mark carrying lower ends do not extend to the lower end of the die block. This construction is provided so that the die block acts as a guide in position- 75

ing the insignia with respect to the dies. The upper ends of the dies extend beyond the upper end of the die block, so that force may be applied directly to the dies rather than to the die block. Since the force required to impress the identification marks upon the wrench is applied directly to the dies, the die block acts primarily as a positioning means. For this reason the dies need not be secured tightly to the die block, as described above, and consequently they may be secured to the die block in a resilient manner, as shown in Figs. 7 and 8.

The construction shown in these figures is substantially the same described above, with the exception that the opening 36 is made somewhat larger than the combined area of the dies 28, and that the screw 38 has been replaced by a resilient spring 42 comprising a flat portion 44 and a bowed portion 46. The flat portion 44 is secured to shoulder 40 of the die block by a screw 48, and the bowed portion 46 extends between one of the dies 28 and the die block, thereby resiliently holding the dies in place.

The identification marks may be readily and simply applied to the wrench by the novel punch device shown in Figs. 9 to 11, inclusive. The punch consists of a bed plate 52 provided with an upwardly and forwardly extending standard 54 of substantially I-shaped cross section. The outer and forward end of the standard terminates in a substantially cylindrical portion 56 provided with a vertical opening in which is mounted a plunger 58. The punch may be secured to any suitable support by bolts or screws (not shown) adapted to pass through holes 60 provided on the base plate.

The plunger 58 is of the type that is moved manually in both directions and is prevented from rotating by a guiding pin 62 extending through the cylindrical front portion 56 of the standard into a vertical slot 64 formed on the plunger 58. The upper end 66 of the plunger is made of reduced diameter and is rounded so that it may be struck with a hammer, or the like, with sufficient force to drive the dies into the wrench.

The plunger is held in its upper or retracted position by a pin 68 having a rounded end and slidably mounted in an opening 70 formed in an external boss 72. The rounded end of the pin is adapted to be forced into an annular groove 74 formed on the plunger slightly below the middle thereof whenever the plunger is raised to a predetermined position. The pin 68 is biased 55 toward the plunger by a helical spring 76 abutting against the pin 68 and a stop screw 80 closing the opening 70. The pin 68 not only serves to hold the plunger in its retracted position, but also prevents free movement of the plunger at all times.

The lower end of the plunger 58 is provided with a head 82 that is substantially elliptical in cross section so as to extend over all the dies, as clearly shown in Fig. 10. In order that the plunger may be inserted in place in the opening in the cylindrical portion 56, the base plate 52 is provided with an elliptical opening 84 through which the plunger may be inserted into the opening. The opening 84 is covered by an anvil 86 extending the width of the bed plate and provided with a central raised portion 88 upon which the wrench is placed for marking. The anvil may be slidably mounted in the bed plate or secured thereto, as shown, by a pair of screws 90.

When it is desired to mark a wrench provided

with insignia of a design described above, suitable marking dies 28 are first selected from a font containing a group of dies. Usually the font contains twenty-six dies corresponding to the number of letters in the alphabet, but, as stated previously, other identifying marks may be used. The selected dies are then placed in the die block 34 where they are held in position either by the set screw 38 or the resilient spring 42, depending on which form of die block is used. The wrench is then placed on the raised portion 88 of the anvil 86 in such manner that the insignia 16 is located directly below plunger 58. The die block 34 containing the dies 28 is thereafter placed over the insignia. If the plunger is in its retracted position with pin 68 in groove 74, then a relatively slight pressure must be applied to the plunger to force the pin out of the groove and the plunger into engagement with the tops of the dies; that is, to the position indicated in Fig. 9.

After the plunger has been brought into this position, a heavy blow may be struck on the upper end 66 of the plunger to force the dies into the wrench. After the blow has been struck, the wrench may be lifted to the position shown in phantom in Fig. 10 to lift the plunger to its retracted position with pin 68 against the groove 74.

It may be seen that the dies need not be accurately positioned within the die block because of the fact that the dies may move relative to the die block. If the die block extends too far below the ends of the dies, the die block will strike the wrench first, but the dies may be moved to their proper marking positions by applying a slight amount of pressure to the plunger, thereby forcing the dies to move relative to the die block.

From the above description, it is seen that the identification marks are applied to the wrench surface enclosed by the insignia and simultaneously to both sides of the central rib 18. When properly applied the finished tool will have the identification marks impressed thereon as shown in Fig. 12.

Because of the close proximity of the long sides 20 of the insignia and the central rib 18 to each other, it is exceedingly difficult to efface the identification marks. In case the original marks are removed and new ones substituted, the alteration may be detected from an inspection of the relative height of the insignia with respect to the wrench heads 10 or the wrench handle surface inside or outside the insignia, as previously described.

While the ribbed octagonal insignia described above is a preferred insignia, other forms may be used as well. For instance, a plurality of ribs similar to the single central rib 18 described may be used, and it is not necessary that the insignia have an octagonal shape. As a further possible modification, a portion of each identification mark may be outside the enclosing insignia as well as inside.

The invention described above is particularly adapted to be practiced by supplying a quantity of tools provided with a certain insignia and corresponding marking dies to individual dealers. Purchasers of tools, be they individuals or organizations employing a number of workers, can obtain tools suitably marked from the dealer. Once marked the owners thereof are less likely to lose them because of the difficulty of effacing the identification marks and applying new ones, and also because of the detection of alteration.

The invention is also adapted to be practiced in large work shops where the tools are distributed from a central tool room. The tools in any particular tool room or shop may be provided with a distinctive insignia and the attendant would be provided with a corresponding die. The attendant would thus be the only person able readily to mark the tools whereby the likelihood of loss would be decreased, as explained above.

It should be understood that the above described invention may be modified in various ways, as indicated above, by those skilled in the art, and that it is not limited to the above described embodiment.

I claim:

1. A tool comprising sections of different thickness, the thicker of which has a plane surface spaced a predetermined distance from the surface of the thinner, an insignia formed on the surface of the thinner of said sections comprising a rib of uniform height extending outwardly from the surface to the plane of the surface of the thicker section, a part of said rib enclosing a relatively narrow portion of the surface of the thinner section, and a second part dividing the enclosed surface into two parts, and identification marks formed on the enclosed surface with a part of each mark on each side of the dividing rib, whereby the identification marks may be effaced only with difficulty and by use of special tools and when effaced the alteration may be readily detected by noting the planes of the surfaces of the tool sections and the rib.

2. A tool adapted to be marked with a die provided with identification marks crossed by a groove comprising sections of different thickness, the thicker of which has a plane surface spaced a predetermined distance from the surface of the thinner, and an insignia formed on the surface of the thinner of said sections comprising a rib extending outwardly from the surface to the plane of the surface of the thicker section, whereby the tool may be marked readily only with a grooved die, alteration of the marks rendered difficult, and alterations readily detected by comparison of the height of the insignia and the surfaces of the tool.

3. A tool comprising sections of different thickness, the thicker of which has a plane surface spaced a predetermined distance from the surface of the thinner, an insignia formed on the surface of the thinner of said sections comprising a rib extending outwardly from the surface to the plane of the surface of the thicker section, and an identification mark formed on the surface of the thinner section with a part of the mark on each side of said rib.

4. A tool adapted to be marked with a die provided with identification marks crossed by a groove comprising sections of different thickness, the thicker of which has a plane surface spaced a predetermined distance from the surface of the thinner, and an insignia formed on the surface of the thinner of said sections comprising a rib extending outwardly from the surface to the plane of the surface of the thicker section and

enclosing a portion of the surface of the thinner section, said rib having a portion adapted to receive the groove whereby the tool may be marked readily only with a grooved die, alteration of the marks rendered difficult, and alterations readily detected by comparison of the height of the insignia and the surfaces of the tool.

5. A tool comprising sections of different thickness, the thicker of which has a plane surface spaced a predetermined distance from the surface of the thinner, an insignia formed on the surface of the thinner of said sections comprising a rib extending outwardly from the surface to the plane of the surface of the thicker section and enclosing a portion of the surface of the thinner section, and an identification mark formed on the surface of the thinner section with a part of the mark on each side of the rib.

6. A tool adapted to be marked with a die provided with identification marks crossed by a groove having formed thereon an identifying insignia consisting of an integral rib of uniform height extending outwardly from a portion of the surface of the tool to the plane of another portion of the surface, a part of said rib defining a substantially oblong octagon adapted to fit around the end of the die and another part of said rib being located parallel to the long sides of said octagon, thereby dividing the surface of the tool enclosed by the first part into two substantially equal portions said other part of the rib being adapted to receive the groove formed in the die whereby identification marks may be readily applied to the enclosed tool surface.

7. A tool having formed on a surface thereof an identification insignia defined in part by a continuous rib of predetermined length and height projecting from said surface, and grooves formed in said surface of the tool in the form of unitary characters or symbols having portions thereof abutting and extending from the opposite sides of said rib.

8. A tool having formed on a surface thereof an identification insignia defined in part by a rib extending outwardly from the surface of the tool, said rib enclosing a relatively small area of said tool's surface and having an unbroken portion of predetermined length and height dividing the enclosed area into two parts, and grooves formed in each part of said surface area in the form of unitary characters or symbols having portions thereof abutting and extending from the opposite sides of said unbroken rib portion.

9. An article adapted to be marked with an insignia by a die provided with identification markers crossed by a slot, said article having formed on the surface thereof a continuous rib of predetermined length and height projecting from said surface adapted to receive the slot of said die, and identification marks in the form of grooves formed in the surface of the tool by the markers of said die, said grooves having unitary character or symbol forming portions which extend in part from and about each side of said rib as an insignia forming portion thereof.

THERON L. HEDGPETH.
